CASH REGISTER

William Leonard Paden, Dayton, Ohio

Application September 7, 1935, Serial No. 39,582

32 Claims.

(Cl. 235—14)

This invention relates to cash registers and indicators, and more particularly to a register mechanism of the lever operated type having amount determining means for setting up the sum to be registered in advance of the actuation of the registering mechanism.

The present register construction embodies a succession of banks or units of similar construction arranged side by side, and corresponding to cents, dimes, dollars, tens of dollars, and hundreds of dollars respectively, only one of which is illustrated. Each unit or bank of mechanism includes a dial operated setting element movable through different ranges of adjustment according to the value to be set up and an associated actuating lever movable through a full stroke motion at each operation for registering the amount determined by the dial setting, together with gear segments movable in unison with the actuating lever through distances proportionate to the amount determined by the dial setting for correspondingly actuating accumulator and indicator devices. A variable stop device for arresting the corresponding indicator in predetermined position is adjusted automatically by operation of the mechanism as is also means for connecting and disconnecting the accumulator devices and preventing overthrow thereof.

While one of the more serious objections to lever operated register mechanisms has been the excessive manual effort and power required for actuation of the register, which power requirements usually increase with the registry of sums embodying higher digits and consequent longer movements of the register mechanism elements, one of the important features of the present construction is the provision of counterbalancing means and automatic variation of differential tension upon the actuating parts during movement whereby the resistance to operation is minimized and the tension is equalized throughout the full stroke operation.

The object of the invention is to improve the construction as well as the means and mode of operation of cash register mechanism, whereby it may not only be economically manufactured, but will be more efficient in use, of greater accuracy in operation, easily operated, and unlikely to get out of repair.

A further object of the invention is to provide a flexible dial type setting mechanism, whereby the amount to be registered may be predetermined and any error in setting up the amount readily corrected before registry thereof.

A further and important object of the inven-

tion is to provide automatic tension equalizing and counterbalancing means which will automatically compensate for variation of power required for registering different sums.

5 A further object of the invention is to provide compensating means whereby the expenditure of effort necessary for actuation of the mechanism is reduced to minimum.

A further object of the invention is to provide 10 amount setting and register actuating means for each bank or unit of mechanism, which may be actuated by a single continuous movement, or may be separately operated at the will of the operator.

15 A further object of the invention is to provide a plurality of actuating devices for the register mechanism, any one of which may be operated to register a sum set up collectively in the corresponding bank and other banks of mechanism.

20 A further object of the invention is to enable the registration of a previously predetermined sum by actuation of any one of several operating devices.

A further object of the invention is to enable 25 the amount to be registered to be preindicated by setting up the denominational figures of the sum in a straight line normal reading relation.

Further objects of the invention are to provide 30 improved indicator arresting means to prevent overthrow thereof, and to provide improved means for controlling the connection and disconnection of accumulator mechanism at predetermined times in the cycle of operation.

A further object is to provide a cash register 35 mechanism of compact construction whereby a register of comparatively large capacity may be made to occupy a relatively small space.

A further object of the invention is to provide 40 a mechanism of which a relatively large proportion of the parts may comprise stampings and other economically manufactured parts whereby the costs of manufacture may be minimized.

A further object of the invention is to provide 45 a cash register mechanism having the meritorious features and the advantageous structural characteristics herein mentioned.

A further object of the invention is to provide 50 a mechanism whereby the amount can be set up and registered in one continuous movement.

With the above primary and other incidental objects in view, as will more fully appear in the specification, the invention consists of the features of construction, the parts and combinations thereof, and the mode of operation, or their

equivalents, as hereinafter described and set forth in the claims.

In the accompanying drawings, wherein is shown the preferred but obviously not necessarily the only form of embodiment of the invention:

Fig. 1 is a side elevation of the assembled apparatus, forming the subject matter hereof, with the parts shown in their normal or "home" position.

Fig. 2 is a plan view showing the arrangement of levers pertaining to two banks or units of the register mechanism with the indicator and counter devices removed. Other banks with like system of levers may be arranged side by side to any desired extent to afford the required capacity.

Fig. 3 is a fragmentary view of the apparatus, illustrating the relation of the parts after an amount has been set up but before registry thereof.

Fig. 4 illustrates the parts in their final operated relation.

Fig. 5 is a front elevation of the setting and actuating levers.

Fig. 6 is a detail view of a modified form of positive latch release.

Figs. 7, 8 and 9 are detail views of the operating levers and their terminal extensions.

Like parts are indicated by similar characters of reference throughout the several views.

The register mechanism includes a succession of identical units or banks of mechanism, assembled side by side upon a common main shaft and operable to register denominational sums, the actuating elements of which, however, are interconnected for unison operation through the main shaft.

Referring to the drawings, 1 is the end plate of the machine frame, two of which are interconnected in spaced relation by interconnecting frame rods and shafts with succeeding denominational banks or units of mechanism pertaining to cents, dimes, dollars, tens and hundreds of dollars, interposed side by side therebetween. Mounted in the end plates 1 and extending centrally through the machine is the main shaft 2 upon which the amount determining and operating parts are mounted.

Pivotaly mounted upon the main shaft 2 for free oscillatory movement relative thereto is the setting lever comprising a pair of parallel interconnected spaced arms 3 carrying at their forward free ends an arcuate dial head 4 having in its forward face a succession of finger holes 5 corresponding to the digits zero to nine and so numbered. At its rear side, the dial head 4 is provided with a succession of notches 6, one for each position of adjustment and corresponding to the numbered finger holes 0 to 9.

Loosely journaled also upon the main shaft 2 is the actuating lever which comprises a pair of parallel spaced arms 7 extending exteriorly of the arms 3 of the setting lever, and interconnected at their forward ends where they carry a dependent arcuate head 8. Intermediate the parallel spaced arms 3 and 7 of the setting and actuating levers which are loosely journaled upon the main shaft 2, is a coupler arm 9 which is fixedly secured upon the main shaft 2 by pinning as at 10, or otherwise, and which carries at its forward free end an upwardly extending arcuate arm or head 11.

Loosely journaled upon the main shaft 2, intermediate the arms 3 and 7 of the setting and actuating levers and intermediate such arms and

the coupler arm 9, is a pair of oscillatory gear segments 12 and 13, one of which pertains to the accumulator mechanism and the other to the indicator. These gear segments are provided with radially extending arms 14 extending into the path of a contact lip or lug 15 upon one of the setting lever arms 3, which, upon continued movement of the setting arm under influence of the actuating lever as hereinafter described, will engage the gear segment arms 14 to oscillate the gear segments 12 and 13 through a movement corresponding to the amounts set up by the initial adjustment.

Mounted upon transverse frame rods 16 connecting the end plates 1 and extending in dependent relation between the parallel spaced arms 3 and 7 of the setting and actuating lever is an arcuate finger 17 concentric with the center of oscillation of the several parts and the main shaft 2. Pivotaly mounted at 18 upon a dependent portion of the actuating lever 7 and adjacent to its arcuate head 8 is a locking arm 19, to the lower end of which is connected an actuating spring 20 which tends to oscillate the end of the locking arm 19 above the pivot 18 outwardly. The locking arm 19 is normally held against such movement under influence of the retracting spring 20 by a finger 21 abutting upon a stop lug 22 projecting from a depressible slide 23 mounted upon the arcuate head 8 of the actuating lever and having at its upper end a finger contact pallet 24 by which the slide may be depressed against the resistance of a retracting spring 23a to release the locking arm 19. At its upper end, the arm 19 carries a stud 25 normally positioned above the upper end of the stationary arcuate arm 17, and by its engagement therewith serving to lock the actuating lever 7 in its elevated normal or home position.

The head or arm 11 of the coupler arm 9 is provided with a notch 26 opposite the stud 25 of the locking lever 19. This notch 26 in the coupler arm is normally positioned opposite an unnotched part of the setting lever head 4 below the zero position. Upon oscillation of the setting lever 3 by depression of the dial head 4, the notch 6 corresponding to any one of the selected digits may be brought into registry with the notch 26 of the coupler arm. In setting up any sum to be registered, the operator by setting his finger in the dial opening 5 corresponding to the desired digit draws the setting lever head 4 and with it the arms 3 downwardly about the journal connection upon the main shaft 2 until such movement of the setting lever is arrested by the engagement of the operator's finger with the contact pallet 24 of the slide 23.

The depression of the slide under impact of the operator's finger with the pallet 24 withdraws the stop 22 from the path of the locking arm finger 21, allowing the finger to oscillate under the influence of the spring 20 to shift the locking stud 25 off the end of the arcuate finger 17, thereby unlocking the actuating lever and simultaneously moving the stud 25 into the notch 26 of the head or arm 11 of the coupler arm 9 and into whichever one of the notches 6 of the head 4 which has been registered with the notch 26 by the movement of the setting lever.

The oscillatory movement of the locking lever 19 by movement of the stud 25 from over the end of the concentric arcuate arm 17 into the registering notches 6 and 26 interlocks the actuating lever 7 and setting lever 3 with the

coupler arm 9 for unison movement. The initial setting movement of the setting lever 3 has moved the contact ear or lug 15 a predetermined distance toward the gear sector arms 14, corresponding to the selected digits. At this stage the parts will have been moved from the position shown in Fig. 1 to that shown in Fig. 3, wherein the setting lever 3 will be locked in a depressed position in its relation with the actuating lever 1 and coupler arm 9 which still remain in their normal positions. However, prior to movement of the actuating lever from its home position, the setting lever and dial head may be readjusted to correct any error in the initial setting.

The notches 6, in the inner face of the dial head 4, are of slightly rounded or cam shape, and upon slight upward effort being applied to the dial head 4, the detent stud 25 may be cammed out of any one of these notches 6, thereby permitting readjustment of the setting lever. In lieu of such movement, the pallet 24 may be manually elevated causing the lug 22 to move upward, and by reason of the spacing between the end of the finger 21 and the point of contact of the pin 22' on the actuating lever 1, and the arcuate slot 21', camming the finger 21 rearward to oscillate the lever 19 and withdraw the stud 25 thereby permitting the setting lever to be retracted by spring tension. More specifically, members 19-21 form a bell crank, and when force is applied to one arm of a bell crank it will rotate so as to bring the direction of the force application into line with the reacting force which passes through the pivot. The line of force and the line of reaction must coincide in order that the bell crank be stable, and as the line of force cannot coincide with the line of reaction the bell crank 19-21 rotates until 21 clears 22 which releases the force from the finger. The end of the finger 21 of the arm 19 which passes over the stop lug 22 when the pallet is depressed is, if desired, slightly inclined or cammed sufficiently that manual upward pressure upon the pallet will assist in the retraction of the finger 21 and with it the stud 25. However, when the actuating lever has been moved from its home or normal position by a continued downward pressure upon the finger pallet 24 thereby carrying the locking stud 25 downwardly past the upper end of the arcuate stationary arm 17, the stud 25 will be held in the registering notches 6 and 26 of the dial head 4 and coupler arm 9 respectively by the arcuate bar 17, and will be prevented from escape from such registering notches during the entire downward and return movement of the parts until the stud 25 is again elevated above the upper end of the arcuate bar 17 in the normal returned position of the actuating lever. During the time the operated parts are away from normal position, the actuating levers pertaining to unused denominational banks are locked in home position by the arms 11 of the corresponding coupler levers, which, moving at every operation, lock the detent studs 25 of the unused bank over the top of the stationary bar 17.

One arm 3 of the setting lever is provided with a dependent portion 27 to accommodate an angular cam slot 28 therein, the dependent portion of which is concentric with the center of oscillation of main shaft 2, and the radial portion of which is slightly curved or arcuate. The coupler arm 9 is provided with a coating arcuate cam slot 29 curved in reverse direction to that of the radial portion of the slot 28. The cam slots 28 and 29, in the setting lever and coupler arm respectively, extend in transverse or intersecting relation, and receive at their point of intersection a roller stud 30 in the lower end of an indicator stop bar 31. The roller stud 30 engages in both of the intersecting slots 28 and 29. As the oscillatory movement of the setting lever 3 relative to the coupler arm 9 is effected, the point of intersection of the cam slots 28 and 29 is varied toward and from the center of oscillation. The roller stud 30 is thus correspondingly shifted toward and from the main shaft 2 whereby, upon unison movement of the parts under influence of the actuating lever 1, a greater or less longitudinal movement is transmitted to the indicator stop bar 31 according to the degree of initial relative adjustment of the setting lever which in turn is dependent upon the selected digit of the dial head 4.

The stop bar 31 in turn positively arrests the indicator in position corresponding to the selected digit and prevents overthrow thereof.

There are two levers, to wit, the setting lever and the actuating lever, the setting lever being movable relatively to the actuating lever different distances in accordance with the amount 1 to 9 to be set up, and which movement of the setting lever does not effect any adjustments of the other mechanism. At the end of this preliminary independent movement of the setting lever, it is locked to the actuating lever for additional movement therewith.

The actuating lever has a constant range of movement and moves through its full stroke until arrested by the stop rod 55 at each operation. This movement of the actuating lever is sufficient to carry the registering mechanism through a range ample to register 9, if the setting lever has previously been set for a "9" registration, plus sufficient movement to lock the accumulator in operative position and unlock the indicator. Such full stroke movement of the actuating lever is correlated with the idle movement between the contacts 14a and 15 by initial adjustment of the setting lever, which is capable of a nine-step movement independently of the actuating lever and also movement in unison therewith.

Assuming the setting lever is initially moved independently of the actuating lever a distance of three steps, this causes the contact 15 to approach the head 14a a distance of three steps. At the end of this initial three-step movement the setting lever is locked to the actuating lever and both levers are moved in unison through the additional nine-step range of the operating lever. Thus, the interlocked levers will move idly through six steps before the contacts 14a and 15 engage and thereafter will move an additional three steps during completion of the full stroke movement of the actuating lever, carrying with it the gear segment and actuating the accumulator to add 3 thereon. The setting lever will have initially moved through a three-step movement independently of the actuating lever to set the contact 15 in relation to the contact 14a and will then have moved nine steps more in unison with the actuating lever, of which six steps are idle, to bring the contacts 14a and 15 together. During the final three steps of movement, the gear segments 12 and 13 will be carried along in unison to actuate the accumulator and set the indicator. It will be noted that the gear segments 12 and 13 or the contact 14a are not at any time interlocked with the setting or the actuating lever.

The initial movement of the setting lever independently of the actuating lever is limited by the engagement of the operator's finger with the operating lever whereupon the levers are interlocked for further unison movement. That is, whatever the extent of such independent movement may be, it is limited by the engagement of the operator's finger with the actuating lever, and the interlocking of the levers occurs at such limit of independent movement.

Inasmuch as the setting lever 3 initially moves independently of the actuating lever and coupler arm in order to set up the amount to be registered and is held in its adjusted relation by the engagement of the detent stud 25 in one of the notches 6 corresponding to the selected digit, the dials pertaining to different denominational banks may be operated in succession or together to correspondingly adjust the setting levers 3 of the different banks or units to set up a sum containing cents, dimes, dollars, tens of dollars, and hundreds of dollars as may be desired, and before the actuating lever is operated to register such sum the setting levers may be readjusted to correct any error. However, when such sum has been set up, the setting levers and actuating levers of the different banks or units have been interlocked with the corresponding coupling arms for unison movement. In the event that any one or more setting levers pertaining to different banks of mechanism have not been operated, the levers of such bank will not be interlocked with the corresponding coupling arm since the stud 25 in such event will be held out of engagement with the notch 26 of the coupling lever by the unnotched portion of the head 4 opposite the zero position. Therefore, the coupling arm 9 of any such unoperated bank or unit will be free to move downwardly with the oscillation of the shaft 2 independently of the setting lever 3 and actuating lever 7 which will remain in their normal elevated or home position during subsequent operation of the mechanism.

After the dials and setting levers pertaining to the selected banks of mechanism have been adjusted to set up the desired sum to be registered, it is quite immaterial which actuating lever shall be depressed to register the amount. Since the actuating lever 7 of each bank of mechanism of which the dial 4 and setting lever 3 have been adjusted is interlocked with the corresponding coupling arm 9 of such bank by the engagement of the detent stud 25 and since all of the coupling arms 9 are pinned or otherwise fixedly secured to the main shaft 2, all of such actuating levers 7 will move in unison.

Fixedly connected to the main shaft 2 at one end thereof is a segment 32 having therein a series of notches 33 engaged by a full stroke pawl 34 which is reversible only beyond the limit of the notched portion of the segment. The engagement of the pawl 34 with the notched portion 33 of the segment 32 compels a full movement of the actuating mechanism, first in one direction and then in the other. During the downward movement of the interlocked setting and actuating levers and coupling arm 9, the contact ear or lug 15 upon the setting lever arm 3 will engage with the arms 14 of the respective gear segments 12 and 13, and will carry such gear segments about the shaft 2 in unison with the movement of the interlocked levers.

The contact lug 15 upon the setting lever 3 will move idly a greater or less distance before engaging the gear segment arms 14 according to

the position to which the setting lever has been initially adjusted. After its engagement with the gear segment arms 14 it will oscillate the gear segments 12 and 13 in unison with the movement of the lever throughout the remainder of its travel range a distance proportionate to the initial setting of the lever 3 and dial head 4. The gear segment 13 intermeshes with a gear segment 36 journaled upon a transverse frame rod 37 and having an opposite toothed portion 36a intermeshing with the gear pinion 38 connected with an indicator wheel 39. The gear segment 36 has therein a concentric slot 40 in which engages a stud 41 carried by the upper end of the indicator stop bar 31. Normally the stud 41 engages the upper end of the concentric slot 40 in the gear segment 36.

As the setting lever 3 is initially adjusted relative to the coupling arm 9, thereby varying the point of intersection of the cam slots 28 and 29, the position of the upper end of the indicator stop bar 31 is not changed but the stop bar will in effect swing slightly about its pivotal stud 41 at the upper end of the slot 40 as the roller stud 39 changes its position toward or from the main shaft 2 as the point of intersection of the cam slots 28 and 29 is varied by the adjustment of the setting lever.

Due to such shifting of the relation of the roller stud 39 to the center of oscillation a greater or less movement is transmitted to the indicator stop bar 31 by the uniform full stroke movement of the bars at each operation. That is to say, if the setting lever has been adjusted to the 1 position, the roller stud 39 will be spaced a greater distance from the center of oscillation and hence the bar 31 will be given a greater degree of movement than if the setting lever has been adjusted to the 9 position, which causes the roller stud 39 to be adjusted close to the opposite ends of the intersecting cam slots 28 and 29 and hence close to the center of oscillation where the full stroke movement of the actuating parts will transmit but a relatively short movement to the indicator stop bar 31.

This adjustment of the indicator stop 31, of course, occurs during the initial adjustment of the setting lever by which the sum to be registered is set up before the register mechanism is actuated. Upon depression of the actuating lever 7 which has been interlocked with the setting lever 3 and coupling arm 9 as before described, the indicator stop arm 31 is drawn downwardly, and the gear segments 13 and 36 are actuated to rotate the indicator through proportionate degrees to indicate the amount set up on that particular bank.

During such movement of the indicator, the oscillation of the intermediate gear sector 36 will have brought the opposite end of the concentric slot 40 into engagement with the stud 41 in the end of the stop bar 31, thereby arresting the segment 36 and with it the indicator 39 actuated thereby. The indicator 39 is held in its adjusted position by a spring detent finger 42 engaging with a star-wheel or notched disc 43 connected to and rotating in unison with the indicator wheel 39.

The spring detent finger 42 and an oscillatory lever 44 are carried by shaft 45 journaled in the end plates 1, one end of which is connected with a retracting spring 46. The opposite end of the rock-lever 44 has a pin and slot connection 47 with a bell crank lever 48 mounted upon a transverse frame rod 49. At its free end, the

bell crank lever 48 carries a stud 50 cooperating with a cam dog 51 pivoted at 52 to one side of the segment 32 and having a limited range of oscillatory movement about its pivotal connection against the tension of a retracting spring 53.

The segment 32 being pinned or otherwise fixedly secured to the main shaft 2 and oscillating in unison with the depression of any one of a series of actuating levers 7 by its initial movement forces the inclined end of the cam dog 51 against the stud 50, causing the bell crank lever 48 to be oscillated and thereby transmit motion to the lever 44 against the tension of the spring 46 to withdraw the spring detent arm 42 from engagement with the star wheel 43, thereby permitting the indicator wheel 39 and associated gear segments 36 and 13 to return to normal preparatory to being reset by the continued movement of the actuating mechanism.

During the continued movement of the actuating levers 7 and the segment 32, the stud 50 of the bell crank lever 48 will ride over the top of cam dog 51 holding the locking detent 42 out of engagement with the star wheel 43 during the downward or operating stroke of the actuating lever. At the limit of the movement of the segment 32, the pin 50 will pass beyond the pivotal end of the cam dog 51, and during the return oscillation of the segment, the stud 50 will pass idly beneath the cam dog, raising the latter against the tension of its retracting spring 53 which, as the parts return to their normal positions at the completion of the operation, again positions the cam dog 51 for operative engagement with the stud 50 at the next operation.

The segment 32 is limited in its oscillatory movement by engagement with a transverse frame rod 54 and at the same time the head 8 of the actuating lever 7 engages with a transverse frame rod 55 which also serves as a limiting stop. During the return movement of the segment 32, as before described, the detent arm 42 engaging with the notched disc or star wheel 43 holds the indicator wheel 39 in its operated position. The actuating gear segments 13 and 36, by which motion is transmitted to the indicator wheel, are also held in their advance or operated positions until the next cycle of operation of the mechanism when the action of the cam dog 51 in elevating the bell crank lever 48 releases the indicator and related gear segments 13 and 36 for resetting. The oscillatory movement of the parts under influence of the actuating lever 7 also effects the interconnection of the accumulator devices with their actuating segment 12.

The accumulator mechanism indicated at 60 is carried upon a swinging frame 61 pivoted at 62 to a stationary portion of the main frame of the register. The accumulator devices, which may be of conventional form and hence have not been shown in detail, are provided with accumulator gears 63 moved into and out of intermeshing engagement with the gear sectors 12 by which the accumulator gears 63 are rotated distances proportionate to the digits set up in the corresponding banks.

The accumulator mechanism is lowered into operative relation with the actuating gear segments 12 during the movement of the parts in one direction and elevated therefrom during the return motion by means of a double cam lever 64 carried by the oscillatory segment 32 and pivoted to a supporting finger 64' thereon at 65 within an irregular opening 66 in the segment. The cam lever 64 is movable about its pivotal 75

connection against the tension of a retracting spring 67. A stud 68 upon the swinging counter frame 61 projects within the opening 66 into engagement with the oscillatory cam member 64.

5 In the normal position of the parts, this stud 68 is positioned at the forward end of the cam member 64, as is shown in Fig. 1.

Upon the initial actuating movement of the segment 32, the stud 68 is cammed downwardly

10 and passes beneath the cam member 64 as the segment oscillates. This downward movement of the stud 68 carries with it the frame 61, drawing the accumulator gears 63 into intermeshing engagement with the actuating gear segments 12.

15 At the limit of the actuating movement of the parts, the stud 68 will have passed beyond the rear end of the cam member 64 and the cam member will have been passed into the return path of the stud by its retracting spring 67.

20 Thereupon the return oscillation of the sector 32 will cause the stud 68 to climb upwardly and pass over the top of the cam member 64, lifting the accumulator frame 61 and disengaging the accumulator gears from the actuating segments 12 during the return movement of the parts. The stud 68 finally comes to rest in the notch 68' to maintain the accumulator mechanism in up position pending a subsequent cycle of operations as just described.

25 30 The accumulator device being lifted out of engagement with the actuating gear segment 12, the latter returns to its normal or home position with the return under spring influence of the remainder of the actuating mechanism. The indicator wheel 39 being held in its operated position by the detent arm 42, the actuating gear segment 13 therefor remains in its operated position and does not return until the initiation of the succeeding cycle of operation.

35 40 The several operated parts are returned to normal by retracting springs 73 and 78 associated with the setting and actuating levers respectively and with the coupling arms and thus with actuating segments 12 and 13 for the indicator and accumulator devices. The locking stud 25 is held in engagement with the registering notches 6 and 26 in the dial head and coupler arm respectively until the actuating lever 7 has reached its normal or home position, and the locking stud 25 has been elevated above the upper end of the 45 concentric stationary finger 17 whereupon the stud 25 will be cammed out of the registering notches by the continuing upward movement of the setting lever and will be forced over the end 50 of the finger 17 by the unnotched portion of the dial head below the notches 6 and opposite the zero position where it is locked by the pallet 24 to hold the actuating lever 7 in its retracted position. During this return movement, the stud 55 55 of the bell crank lever 48 will have traveled beneath the cam dog 51 and assumed its normal position at the forward end thereof while the stud 68 of the accumulator frame 61 will have traveled over the top of the double pivoted cam 60 65 64, and assumed its normal position at the forward end thereof, as shown in Fig. 1.

The retracting springs for the several operative parts are mounted for automatic equalizing adjustment toward and from the center of oscillation of the spring actuated member whereby, as the degree of movement increases which would normally increase the spring tension, the spring moves toward the center of oscillation a proportionate distance. Briefly stated, the retracting springs which are of the helical tension type, are

slidably connected at their opposite ends with spaced guides which change their relative angular relation in unison with the movement of the part to be retracted, the sliding adjustment of the spring upon its guide effecting a progressive change of leverage by which, as the tension of the spring increases, the leverage through which it reacts is shortened and vice versa. This automatic equalization of the spring tension against the yielding resistance of which the various parts are operable is considered an important and highly desirable feature of the present construction.

Referring to the drawings, the actuating levers 7 are each provided with slotted arcuate arms 70 which move in unison therewith to different approximately radial positions about the center of oscillation or main shaft 2.

Mounted upon transverse frame rods 71 in the bottom of the main frame is a series of slotted guide bars 72. Connecting the oscillatory guide arms 70 and the corresponding stationary guide bars 72 in the main frame of the machine is a series of helical tension retracting springs 73. The springs 73 are provided at their opposite ends with heads 74, preferably equipped with small rollers 75 engaging within the guide slots of the arms 70 and bars 72 for to and fro shifting motion therein.

As the actuating lever 7 is oscillated, the arms 70 moving in unison therewith vary their angular relation with the relatively straight guide bars 72. The slots in the arms 70 are disposed upon a curvature such that the progressively changing angular relation of the curved slots will cause a shifting movement of the spring head 74 relative thereto under constant control. That is to say, the roller bearing head 74 will not rush suddenly from one end to the other of the guide slots, but will gradually move therein as the angularity of succeeding portions of the curved slot change with relation to the straight guide bars 72. Thus at the beginning of the movement of the actuating lever 7 the spring heads 74 will be positioned at the extreme outer ends of the slotted arms 70 where the tension of the retracting springs 73 will be relaxed, but where the effective leverage of the arms 70 will be greatest.

As the lever 7 moves downwardly in its actuating stroke, the upward oscillation of the opposite arms 70 will tend to increase the tension of the retracting springs 73, but coincident therewith the spring will move bodily inwardly upon the arm 70 toward the center of oscillation, thereby correspondingly decreasing the effective leverage, until at the limit of the downward movement of the lever, the spring heads 74 will occupy the position at the inner end of the slotted lever 70 where the effective leverage is the least but in such position the spring will be under its maximum tension. Thus a converse ratio of spring tension to effective leverage is maintained whereby the resistance offered by the retracting spring will be equalized throughout the actuating movement by the bodily movement of the springs through successively parallel planes. By such construction the retracting springs 73 may be so tensioned as to balance the operating parts in any position of adjustment. However, the springs are tensioned slightly beyond the balance point, whereby they will have sufficient power to return the operated parts, but due to the automatic equalization of the tension-leverage ratio, the resistance to movement will be minimum and equal throughout the entire range

of operation. As before stated, the setting lever 3 and dial head 4 are movable relative to the actuating lever 7 and then both levers are movable in unison with each other and with the coupling lever. This latter movement is against the tension of the springs 73. However, the setting lever is provided with a further tensioning spring controlling its movement relative to the actuating lever.

To this end, the setting lever is provided with a slotted arm 76 integral with the setting lever arm 3 and moving in unison therewith. The actuating lever 7 is provided with a dependent slotted guide arm 77. The guide arm 77 is provided with a straight slot therein and corresponds in function and effect to the straight guide bars 72 in the bottom of the frame.

The setting lever arm 76 is provided with an arcuate slot therein and this arm corresponds in function and effect to the arms 70 before described. Interconnecting the guide arm 76 of the setting lever with the guide arms 77 of the actuating lever is a retracting spring 78 having at each end sliding heads 79 provided with anti-friction rollers 80 engageable within and movable to and fro in the guide slots of the respective arms 76 and 77.

When the setting lever 3 is in its normal or home position and the retracting spring 78 is relaxed, the heads 79 occupy the outer ends of the slotted arms 76 and 77, as shown in Fig. 1. As the setting lever is depressed relative to the actuating lever, the angular relation of the arms 76 and 77 being correspondingly changed, the retracting spring being placed under increased tension shifts its position along said arms toward the center of oscillation, thereby decreasing the effective leverage of the arm 76 upon the retracting spring as the tension thereof is increased. Such shifted position of the spring is illustrated in Fig. 4, wherein the retracting spring pertaining to the setting lever is shown in a mid-position since the setting lever has not been adjusted to the full limit of its range of movement relative to the setting lever, while in the same figure the retracting spring 73, pertaining to the actuating lever, is shown at the point of maximum tension and minimum leverage since the actuating lever is shown in Fig. 4 at the limit of its range of movement. By such shifting movement of the retracting spring, the resistance of the setting lever to a movement to register the digit 9 is no greater than that to register digits 1 or 2.

Likewise, during the registering operation the resistance to the depression of the actuating lever 70 is no greater as it approaches the limit of its range of movement than at the beginning of such movement. This equalization of resistance to the movement of the operated parts affords a practical solution for a problem which has long rendered the operation of such mechanism objectionable.

As before described, the indicator, and its actuating segments remain from one operation until the succeeding operation in their adjusted positions in which they have been positively arrested by the stop bar 31. It is not necessary that they be returned to zero preparatory to resetting, unless the corresponding bank of mechanism is not employed. In such case the withdrawal of the detent 42 from the star wheel 43 will permit the segments and indicator to be retracted to zero by the segment retracting spring corresponding to the spring 73. If a lower number is to be registered in such bank the segments

and indicator return under such spring tension until the setting lever and stop link are intercepted and the parts arrested thereby in the new position. If a higher number is to be registered the indicator and control segments are picked up by the operating parts and moved directly to the new higher setting.

The arm 14 of the accumulator segment 12 carries a lug or ear 14a which overhangs the arm 14 of the indicator segment 13. Hence the positive arrest of the indicator segment in its operated position serves also to arrest the accumulator segment, and prevents overthrow. The stop bar 31 is thus indirectly common to both the indicator and accumulator devices.

It is through the overhanging ear or lug 14a that the motion imparted to the accumulator segment by the setting lever lug 15 is transmitted to the indicator segment. As the parts approach the limit of their movement at the end of each setting operation, the indicator segment 13 and accumulator segment 12 will be traveling in unison with the lug 14a of the accumulator segment arm 14 in overhanging engagement with the arm 14 of the indicator segment and urging it through like motion. The accumulator segment however returns idly to normal under influence of the spring 73 which is effective on the coupling lever 9 after each setting operation, leaving the indicator segment in its operated position.

Upon the release of the actuating lever at the limit of its downward movement, the actuated parts are automatically returned to normal or home position by the action of the retracting springs. At the limit of such return movement the actuating lever 7 will impinge upon the frame rods 16 which form stops for the setting and actuating levers in their home position. The setting lever 3 having been initially advanced relative to the actuating lever 7 and locked in such relation by the detent stud 25 held in engagement by the arcuate finger 17, will return in the same relation in unison with the actuating lever 7 until the latter abuts the frame rods 16 and comes to a sudden stop. The detent stud 25 will then have been carried beyond the end of the locking finger 17 and will be held in the digit notch only by the spring 20. The retractive action of the spring 78 plus the momentum of the setting lever 3 acquired during the return movement of the actuating lever is sufficient to overcome the tension of the spring 20 and the detent stud 25 is cammed out of its notch by the inclined side thereof thereby permitting the setting lever to continue its return movement until it too is arrested by contact with the frame rods 16. The retraction of the detent stud 25 by oscillation of the arm 19 against the tension of the spring likewise retracts the finger 21 out of engagement with the lug 22 on the depressible slide 23, thereby releasing the finger contact pallet 24. Thus the parts are all returned to normal preparatory to the succeeding operation.

To insure positive release of the setting lever 3 upon the return of the actuating lever 7 to normal position and permit the further return of the setting lever 3 to its zero position, the guide finger 17 may be diagonally divided as is shown in Fig. 6. The upper portion 17a thereof is pivoted for swinging movement into the path of the stud 25 under influence of a retracting spring 17b. During the descent of the interlocked levers the stud 25, passing through its arcuate path in close conformity with the convex margin of the fixed guide finger 17, depresses the

upper pivotal portion 17a against the resistance of its spring 17b (Fig. 6) into alignment with the continuing stationary portion of the finger 17, and is thereby held in latching engagement with the several levers locking the setting and actuating levers to the coupling lever for unison motion. However as the actuating and coupling levers approach the limit of their return movement, the free end of the pivoted portion 17a having been projected by the spring 17b into the return path of the stud 25 is engaged thereby. The stud 25 is directed inwardly between the pivotal and stationary portions 17a and 17 and caused to pass to the rear of the former, which thereby cams the stud 25 out of the notch 6 of the setting lever head 4 and the notch 26 of the coupling lever head 11 in registry therewith. Such retraction of the stud 25 releases the setting lever which may then continue its return movement to normal after the actuating lever and coupling lever have come to rest. The stud 25 in its final position overhangs the upper end of the portion 17a, thus locking the actuating lever in its retracted position, but leaving the coupling lever free for independent oscillation until the setting lever is again operated and the pallet 24 again depressed by the operator's finger at the limit of the setting lever motion.

The automatic shifting of the tension springs 30 not only tends to equalize the resistance of the operated part by change of effective leverage in approximate proportion to the degree of movement, but it also governs the return motion, preventing a too rapid action. At the initiation of 35 the return motion the action of the spring is upon a relatively short radius or short leverage which prevents a sudden action, but as the return movement progresses the effective leverage likewise increases. It is quite possible by tensioning the 40 spring to cause the operated part to remain in balanced relation in any position of intermediate adjustment to which it may be moved. In practice the tension is adjusted but a slight degree beyond such balancing tension whereby the 45 overbalancing influence of the spring will be comparatively little to be overcome by manual effort but will be substantially uniform throughout the entire range of movement.

From the above description it will be apparent 50 that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the 55 invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. In a register mechanism having an accumulator, an actuating means for the accumulator including an actuating lever movable through a constant range of movement at each operation, a differentially movable setting lever, operable in advance of the movement of the actuating

lever and relative thereto through distances proportionate to the amount to be registered, and means for interlocking the setting and operating levers one to the other at the end of the relative movement of the setting lever for further movement in unison, and motion transmitting means actuated by unison movement of the levers through at least a predetermined portion of said full range movement of the actuating lever for actuating the accumulator to accumulate thereon the amount determined by the initial relative movement of the setting lever.

2. In a register mechanism having an accumulator, actuating means for the accumulator, including a pair of concentrically mounted levers operable in substantially a common plane, one of which is movable through a constant predetermined range and the other of which is movable relative thereto through a variable range in accordance with the amount to be registered, the lever movable through a constant predetermined range being engageable by the operator's finger at the limit of relative movement of the lever which is movable through a variable finger for continued movement therewith in a single operation, and means for transmitting motion from the levers to the accumulator mechanism during such coincident movement of the levers to accumulate thereon an amount determined by the initial movement of the lever which is movable through a variable range.

3. In a register mechanism having an accumulator, actuating means for the accumulator, including a movable setting dial having a series of finger holes therein, a pair of concentrically mounted levers operable in substantially a common plane, one of the levers being movable through a constant predetermined range and the other lever being connected to and actuated by movement of the setting dial and movable relative to the lever which is movable through a constant predetermined range through a variable range in accordance with the amount to be registered, an operating member extending into the path of the operator's finger when operating the setting dial and the lever movable through a variable range and engaged thereby to arrest the relative movement of the setting dial and the lever movable through a constant predetermined range, the operating member being connected to the last mentioned lever for actuation thereof and operable by the continued movement of the operator's finger, and motion transmitting means for actuating the accumulator mechanism by the coincident movement of the levers to effect accumulation thereon of the amount determined by the initial relative movement of the setting dial.

4. In a register mechanism having an accumulator, actuating means for the accumulator including a pair of concentrically mounted levers operable in substantially a common plane, one of the levers being movable through a constant predetermined range and the other lever being initially movable relative thereto through a variable range in accordance with the amount to be registered, and thereafter movable through an additional range coincident with the first mentioned lever by a single operating movement of the operator's hand, and motion transmitting means actuated by coincident movement of the levers for transmitting a portion of the movement of the lever which is movable through a variable range to the accumulator mechanism to effect accumu-

lation of the amount determined by said initial relative movement of such levers.

5. In a register mechanism having an accumulator, actuating means for the accumulator including a setting member and an operating member relatively movable in a common path of travel, the setting member being initially movable to determine the degree of actuation of the accumulator, a series of spaced finger holds upon the setting member corresponding to different amounts to be registered, a yielding stop carried by the operating member and engageable by the operator's finger for arresting the relative movement of the setting member at the limit of a range corresponding to the amount to be registered, and latch means controlled by the yielding stop for interlocking the setting and operating members for further unison motion through a constant range and means for transmitting at least a portion of the motion of said members to the accumulator for effecting accumulation upon the accumulator of the amount determined by the initial movement of the setting member.

25 6. In a register mechanism having an accumulator, actuating means therefor including an oscillatory member operable to effect the accumulation of a predetermined sum upon the accumulator, said oscillatory member having therein an arcuate slot, a second member in relation with which the oscillatory member is movable having therein a second slot, a helical spring under tension having its ends shiftingly engaged in the respective slots, the arcuate slot in the oscillatory member being contoured and disposed to exert camming action on the spring as the member is oscillated to effect a progressive bodily shifting movement of the spring in said slots toward and from the center of oscillation whereby the resistance of the mechanism to operative movement is automatically compensated and substantially equalized throughout its range of motion.

40 7. In a register mechanism having an accumulator, actuating means therefor including an oscillatory member operable in the cycle of operation necessary to accumulate a given sum upon the accumulator, a tension spring against the yielding resistance of which said oscillatory member is movable, and guide means for the opposite ends of the spring upon which the line of reaction of the spring is automatically bodily shifted through successive parallel planes toward and from the center of oscillation of said member to equalize the resistance of the spring to movement of the members throughout its range of action.

45 8. In a register mechanism having an accumulator, actuating means therefor including an oscillatory member operable in the cycle of operation necessary to accumulate a given sum upon the accumulator, a tension spring against the yielding resistance of which said oscillatory member is movable, a straight guide for one end of the spring and a curved guide for the other end of the spring, one of said guides being movable relative to the other by the oscillation of said member to thereby change their angular relation to each other whereby the spring is caused to progressively bodily shift its position thereon and exert its reaction at greater or less distance from the center of oscillation of said member to substantially equalize its resistance to movement throughout its range of action.

9. In a register mechanism having an accumulator, an actuating means for the accumulator including an oscillatory member and a second member relative to which the oscillatory member is movable, a spring against the yielding resistance of which the oscillatory member is adjustable, a curved guide carried by the oscillatory member, and a straight guide carried by the other member, the opposite ends of the spring being attached to the respective guides and along which they may automatically move toward and from the center of oscillation in unison with the oscillation of said member to substantially equalize the resistance of said member to movement throughout its range of action.

10. In a register mechanism having an accumulator, adjusting means therefor including relatively movable setting and operating members, the setting member being initially adjustable relative to the operating member, a latch normally locking the operating member against movement and operable to release the operating member and simultaneously interlock the setting and operating members at the limit of relative movement of the setting member for continued unison movement of said members to effect accumulation upon the accumulator of an amount determined by the initial relative adjustment of the setting member, and means for releasing the latch at the limit of return movement of the operating member to thereby release the setting member for further return motion independently of the operating member.

11. In a register mechanism having an accumulator, adjusting means therefor of an adjustable setting member including a succession of spaced finger holds corresponding to different amounts to be registered, an operating member relative to which the setting member is independently adjustable, and a portion on the operating member extending into the path of the operator's finger for limiting the independent adjustment of the setting member and by continued movement of the operator's finger actuating the operating member to accumulate on the accumulator an amount determined by the adjustment of the setting member by continuous uninterrupted movement of the operator's finger.

12. In a register mechanism having an indicator, an actuating means therefor including a pair of relatively movable levers, one of which is movable throughout a fixed path to produce indicator actuation, and the other of which is movable varying distances within the path of the first named lever to operatively interconnect the levers with the indicator for actuation of the indicator to a degree determinable by the distance the second named lever is moved through its path.

13. In a register mechanism having an indicator, an actuating means therefor including a pair of concentrically mounted levers relatively and coincidentally movable in substantially a common plane, one of which is movable throughout a fixed path to produce indicator actuation, and the other of which is movable varying distances within a path coincident at least in part with the fixed path of movement of the first named lever to operatively connect the levers with the indicator for actuation of the indicator to a degree determinable by the variable distance the one lever is moved through its path.

14. In a register mechanism having an indicator, actuating means therefor including a

lever, tension means associated with the lever and rendered effective by movement of the lever from unoperated to operated position for returning the lever from operated to unoperated position, and means for effecting shifting of the line of effect of the tension means through successive parallel planes and thereby maintaining the return effect exercised on the lever by the tension means constant throughout lever return movement from operated to unoperated position.

15. In a register mechanism having an accumulator, actuating means for the accumulator including a pair of concentrically pivoted levers one of which is initially movable relative to the other through variable range to set up an amount to be registered and the other of which is movable in unison with the first lever through a further constant range, means for connecting the levers for such unison movement, and means whereby unison movement of the levers is effective to operatively connect the levers with the accumulator mechanism and to effect accumulation thereon of the amount determined by the initial movement of the first named lever.

25. 16. In a register mechanism having an accumulator, actuating means for the accumulator including a plurality of concentrically mounted levers relatively adjustable about a common shaft as an axis, including a setting lever movable through a variable range in accordance with the amount to be registered and an actuating lever movable through a constant range in actuating the accumulator mechanism and effecting registration of the amount determined by movement of the setting lever, a lever pinned to the shaft and movable through a constant range equal to that of the actuating lever at every operation of the mechanism, and locking means operative at the limit of the range of relative

30. 40. movement of the setting lever and the actuating lever for interlocking the several levers one with another for unison movement of the several levers, and means for operatively connecting the interlocked levers to the accumulator for that portion of the unison movement predetermined by the variable adjustment of the setting lever.

45. 50. 55. 60. 65. 17. In a register mechanism having an accumulator, an actuating means therefor including a setting lever movable through a variable range in accordance with the amount to be registered and an actuating lever movable through a constant range, and means effective for transferring to the accumulator mechanism at least a portion of the movement of the actuating lever to effect accumulation on the accumulator mechanism of the amount determined by the movement of the setting lever, a latch means for interengaging the setting and actuating levers for unison operation and engageable by the operator's finger at the limit of variable movement of the setting lever for effecting interconnection of the levers and adapted by continued movement of the operator's finger to effect the unison movement of the setting and actuating levers.

70. 75. 18. In a register mechanism having an accumulator, actuating means for the accumulator including a setting lever movable through a variable range in accordance with the amount to be registered and an actuating lever movable through a constant range and producing actuation of the accumulator mechanism throughout at least a portion of the movement thereof to effect accumulation on the accumulator mechanism of the amount determined by the move-

ment of the setting lever, a latch member normally locking the actuating lever against movement, and latch release means operable at the limit of amount registering movement of the setting lever for releasing the actuating lever, said last named means being effective to simultaneously interlock the setting lever therewith for unison movement of the levers.

19. In a register mechanism having an indicator, actuating means for the indicator including a plurality of banks of operating mechanism each including an actuating lever and another lever forming a part of the coupling between the actuating lever and the indicator, both movable through constant range of movement, a setting lever movable relative to the actuating and second named levers through a variable range in accordance with the amount to be registered, the second named levers of different banks of mechanism being interconnected for unison motion, and latch means operative at the limit of amount registering movement of the setting lever to interlock the setting lever and the corresponding actuating lever with the corresponding second named lever for further unison motion to effect actuation of the indicator and registry thereon of the amounts determined by the operation of different setting levers, the movement of any one of the actuating levers of operated banks being transmitted to the several levers of every other operated bank of the register mechanism through the interconnection between the second named levers.

20. In a register mechanism having an amount indicator, adjusting means for the indicator, indicator actuating means including a setting member and a second member in relation with which the setting member is movable, said second member by its operation serving to produce actuation of the indicator, transverse guides carried by the respective members, the point of intersection of which is progressively changed by the relative movement of said members, and a stop for limiting indicator actuation and having operative engagement with both guides at their common point and adjustable by the relative movement of said members to define the range of operation of the indicator.

21. In a register mechanism of the character described, an indicator and means for producing actuation of the same including a pair of members normally out of operative actuating relationship with the indicator and one of which is capable of oscillatory motion relative to the other to determine the extent of actuation of the indicator, transversely disposed arcuate slots in the respective members, and a stop for the indicator simultaneously engaging in the respective slots and shifted to and from the center of oscillation by the relative oscillation of said member to define the range of actuation of the indicator.

22. In a register mechanism having an accumulator, operating means for the accumulator including an oscillatory member coacting therewith to effect accumulation of a given amount, a yielding resistance against which the oscillatory member is operable, and means effecting automatic bodily shifting of the line of effect of the yielding resistance through successive parallel planes to and from the center of oscillation of said member approximately in proportion to the degree of oscillatory motion thereof whereby the resistance to movement thereof will be substantially uniform throughout its range of action.

23. In a register mechanism having an indicator, an actuating means for the indicator including members movable successively relatively and coincidentally within a predetermined path and effective to produce actuation of the indicator through a portion only of their coincident movement, and means effected by relative movement of the members to determine the extent of actuation of the indicator.

10 24. In a register mechanism having an indicator, an actuating means for the indicator including members movable successively relatively and coincidentally within a predetermined path and effective to produce actuation of the indicator through a portion only of their coincident movement, means effected by relative movement of the members to determine the extent of actuation of the indicator by coincident movement of the members, and means for locking the movable members in a preselected relative position for such coincident movement.

15 25. In a register mechanism having an indicator, an actuating means for the indicator including two members relatively and coincidentally movable within a predetermined path and effective to produce actuation of the indicator through a portion only of their coincident movement, means for locking one of the members against movement, means effected by movement 20 of the other member relatively thereto to determine the extent of actuation of the indicator by coincident movement of the members, and means for releasing the locking means effective on the one member at substantially the limit of 25 relative movement of the other member.

26. In a register mechanism having an indicator, an actuating means for the indicator including two members relatively and coincidentally movable within a predetermined path and effective to produce actuation of the indicator through a portion only of their coincident movement, means for locking one of the members against movement, means effected by movement 30 of the other member relatively thereto to determine the extent of operation of the indicator by coincident movement of the members, means for releasing the locking means effective on the one member, and means for locking the members together for coincident movement.

27. In a register mechanism having an indicator, an actuating means therefor including two members relatively and coincidentally movable within a predetermined path and effective to produce actuation of the indicator through a portion 35 only of their coincident movement, means for locking one of the members against movement, means effected by movement of the other member relatively thereto to determine the extent of operation of the indicator by coincident movement of the members, means for releasing the locking means effective on the one member, means for locking the members together for coincident movement, and means for releasing said last named locking means after completion of movement of the members in actuating the indicator.

28 23. In a register mechanism having an indicator, an actuating means for the indicator including a setting lever and an actuating lever movable successively relatively and coincidentally within a predetermined path to first produce operative engagement of the levers with the indicator for indicating a preselected amount and then produce actuation of the indicator to indicate such amount.

29. In a register mechanism having an indicator, an actuating means therefor including a setting lever and an actuating lever movable successively relatively and coincidentally within a predetermined path to first produce operative engagement of the levers with the indicator for registering a preselected amount and then produce actuation of the indicator to register such amount, and latch means for securing the levers in the relative positions for registry of the preselected amount by their coincident movement.

30. In a register mechanism having an indicator, an actuating means therefor including a setting lever and an actuating lever movable successively relatively and coincidentally to first produce operative engagement of the levers with the indicator for registering a preselected amount and then producing actuation of the indicator to register such amount, the actuating lever being movable throughout a fixed path to actuate the indicator, tension means resisting movement of the levers to operated position and effecting return movement of the levers to unoperated position, and means rendering the degree of resistance and return force applied by the tension means constant.

31. In a register mechanism having an indicator, an actuating means for the indicator including a rotatable member, a series of levers,

two of which move freely about the rotatable member as an axis and another of which is secured thereto against relative movement, the levers moving in unison and in coincident paths to produce indicator actuation, and one being movable relative to the others to determine the degree of actuation of the indicator, mechanism for operatively interengaging the levers with the indicator for actuation thereof, and means effective to interlock all of the levers together for unison movement at the limit of indicator actuation extent determining relative movement of the last named lever.

32. In a register mechanism having an indicator, an actuating means for the indicator including a lever normally disconnected from the indicator and movable throughout a fixed path, a setting lever movable relatively to the actuating lever variable distances and in a fixed path, and means responsive to movement of the setting lever for operatively engaging the levers with the indicator, the construction and arrangement being such that the extent of actuation of the indicator is determinable by the degree of relative movement of the setting lever and the actuating lever in operatively engaging the operating lever with the indicator.

WILLIAM LEONARD PADEN.

CERTIFICATE OF CORRECTION.

Patent No. 2,273,985.

February 24, 1942.

WILLIAM LEONARD PADEN.

It is hereby certified that error appears in the printed specification of the above numbered patent requiring correction as follows: Page 2, first column, line 13, after "Other" insert --denominational--; page 8, first column, line 24, claim 2, for "finger" read --range--; and that the said Letters Patent should be read with this correction therein that the same may conform to the record of the case in the Patent Office.

Signed and sealed this 5th day of May, A. D. 1942.

Henry Van Arsdale,
(Seal) Acting Commissioner of Patents.
